UNITED STATES PATENT OFFICE.

SAMUEL GEORGE TATE, OF WASHINGTON, DISTRICT OF COLUMBIA, ASSIGNOR TO UNION SPECIAL MACHINE COMPANY, OF CHICAGO, ILLINOIS, A CORPORATION OF ILLINOIS.

OVEREDGE-LOOPER MECHANISM FOR SEWING MACHINES.

Application filed July 18, 1924. Serial No. 726,742.

This invention relates to new and useful improvements in sewing machines generally, although more particularly to the over-edge looper mechanism of an over-edge type of sewing machine.

In over-edge sewing machines, such as is shown in Patent 962,974, issued June 28th, 1910, to Lansing Onderdonk, the overedge looper is fulcrumed below the throat plate 10 on a fixed pivot which is located to the left of the needle. This overedge looper co-operates with the under looper to project a loop of thread upwardly around the edge of the work to a position above the work, whereby the needle in its descent will enter said loop. Not only the timing of these stitch forming instrumentalities, but also the points of co-operation must be certain. For instance, the overedge looper in its ascending movement, 15 must pass the under looper at a fixed point relative to the thread eye of said under looper, and at the upper end of its movement the overedge looper must be positioned at a fixed point relative to the needle, whereby 20 the needle will with certainty enter the loop of thread carried upwardly by said overedge looper. Therefore, the radius of the overedge looper must be fixed and consequently the space between the upper surface of the 25 throat plate and the arc prescribed by the overedge looper is limited to such an extent that work of ordinary thickness only can be stitched on such machine. In other words, the stitch forming instrumentalities 30 cannot be adjusted to create sufficient space for the passage of heavy sweater work or the like, under the overedge looper. Furthermore, by pivoting the overedge looper at a point to the left of the needle, it is impossible to locate a horn at the left of the needle 35 around which stockings may be turned when it is desired to hem the upper portions thereof.

One of the important objects of my invention is, therefore, to provide an overedge looper mechanism by which the looper will be caused to travel in a path whereby a considerably increased space between the upper surface of the throat plate and the path of 40 travel of the looper will be obtained, thus permitting heavy sweater work, or the like, to be stitched.

Another important object of my invention is to provide in an overedge mechanism of the

type described, means for varying the path 55 of the looper travel whereby said travel may be adjusted to suit various working conditions.

A still further object of my invention is to support and actuate the overedge looper 60 by means located entirely on the right-hand side of the needle, thereby permitting the positioning of a horn at the left of the needle for use in hemming stockings or other small 65 tubular articles.

These and other objects will in part be obvious and will in part be hereinafter more fully described.

In the accompanying drawings which illustrate one form of my invention—⁷⁰

Figure 1 is a front elevation, partly in section, showing the application of my invention;

Fig. 2 is a view showing more or less diagrammatically, the throat plate, the needle, 75 and the co-operating stitch forming instrumentalities, the needle being at the lower end of this stroke; and

Fig. 3 is an end view of the overedge looper mechanism, parts thereof being shown 80 in section.

Referring to the drawings in detail, 5 designates a throat plate or work support, which is provided with the usual opening through which the threaded needle 6 reciprocates in a vertical plane. The needle 6 is carried by needle bar 7 and the latter is reciprocated from an upper rotary shaft 8 through the medium of a lever 9.

Co-operating with the needle 6 below the 85 throat plate is a threaded under looper 10 which is mounted in a looper carrier 11 pivoted to the machine frame as at 12, below the throat plate and on the right of the needle. The carrier is provided with a rock arm 13 which is connected by a link 13 to an arm 14 on the lever 9. Thus the rotary shaft oscillates the under looper back and forth in a single plane, the looper moving in rear of the needle and toward the right when it 100 enters the needle thread loop, the point of the looper at the end of the looper movement being located a distance well to the right of the right-hand edge of the throat plate 5.

Co-operating with the under looper 10 and with the needle 6 is an overedge looper 15 which may be either a thread carrying looper or a looper of the spreader type, both forms

being recognized in this art as being substituted, one for the other, for the production of either a three-thread or two-thread stitch. Therefore, I employ the term "overedge looper" to include either type of looper. This overedge looper is removably mounted in the upper end of a substantially vertically disposed looper supporting rod 16 which is supported on the machine frame through the medium of sliding pivotal connection which I have designated by the numeral 17. This connection comprises a bracket 18 which is supported on the machine frame at the right of the throat plate by screws 19, 19, which pass through slots 20, 20 to permit lateral adjustment of the bracket. The upper end of the bracket is formed with a bearing opening 21, the longitudinal axis being inclined upwardly from front to rear, and journaled in this bearing is a stud 22 having an opening 23 formed in one end thereof to receive the looper supporting rod 16. This opening 23 is preferably formed as the result of a sleeve 24 which is integral with the stud 22, and the longitudinal axis of said opening is disposed in a plane at right angles to the longitudinal axis of the stud 22. A rock shaft 25 is journaled on the machine frame at the right of the bracket 18 and is located below the horizontal plane containing the connection 17. Fixed to this shaft 25 is a rock arm 26 which is pivoted, as at 27, to the lower end of the looper supporting rod 16. This rock arm 26 is rocked from the main rotary shaft 8 through the medium of a crank and a link 29, the latter being pivotally connected with the rock arm by a pin and slot connection 30 to permit of adjustment to vary the extent of rocking movement of said arm. The rock shaft 25 is inclined upwardly from front to rear and is in parallelism with the axis of the stud 22, and is preferably rocked a distance equally above and below a horizontal line passing through the center of the shaft 25.

In operation, as the needle begins to rise the under looper moves to the right in rear of the needle and enters the needle thread loop, and terminates its right hand movement beyond, that is, at the right of the throat plate. The overedge looper then moves upwardly, due to the movement of the rock arm, and inasmuch as the pivot connection 30 travels in a substantially straight line until the horizontal is reached, the looper will likewise travel upwardly in substantially a straight line. After the connection 30 reaches the horizontal, it will be moved upwardly towards the right and consequently the looper rod will be swung so as to move the looper upwardly and towards the left over the fabric and presser foot, to a position in advance of the needle 6, whereby the latter, which has been rising in the meantime, will with certainty enter the loop of

thread carried by said overedge looper. Thus, by this overedge looper mechanism, the looper is caused to move upwardly for a considerable distance above the upper surface of the throat plate before it begins its lateral movement over the throat plate, the lateral movement being considerably less than the vertical movement. Hence sufficient space between the upper face of the throat plate and the path of travel of the looper will be provided to permit the machine to stitch heavy sweater work, or the like.

It will also be noted that the overedge looper mechanism is entirely disposed on the right of the needle and consequently the space on the left of the needle is clear for the purpose of providing a horn about which stockings or other tubular work may be turned for hemming or other operations.

Having thus described my invention, what I claim as new and desire to secure by Letters Patent is:

1. In a sewing machine, the combination with a work support, a vertically reciprocating needle, a threaded under looper co-operating with the needle below the work support, and an overedge looper co-operating with said under looper and needle to position a loop of thread around and above said work support into position to be entered by the needle during its descent, means for supporting said overedge looper, and devices for moving said supporting means bodily longitudinally and for swinging said supporting means about a fixed center lying in the path of bodily movement of the looper, whereby said looper is moved upwardly substantially in a straight line from a point in cooperation with the under looper to a point well above the work support and thence laterally and upwardly over the work support to a point on the opposite side of the needle so that the needle can enter the loop carried by said overedge looper.

2. In a sewing machine, the combination with a work support, a vertically reciprocating needle, a threaded under looper co-operating with the needle below the work support, and an overedge looper co-operating with said under looper and needle to position a loop of thread around and above said work support into position to be entered by the needle during its descent, and means for supporting and operating said overedge looper comprising a looper supporting rod, a pivotal support for said rod in which the rod slides, and means connected to said rod for moving the same longitudinally in said pivotal support and for oscillating said rod about the axis of said pivotal support.

3. In a sewing machine, the combination with a work support, a vertically reciprocating needle, a threaded under looper co-op-

erating with the needle below the work support, and an overedge looper co-operating with said under looper and needle to position a loop of thread around and above said work support into position to be entered by the needle during its descent, means for operating said overedge looper comprising a looper supporting rod, a pivotal support for said rod in which the rod slides, a rock arm having a fixed fulcrum and having its end pivoted to the rod, and means for oscillating said rock arm.

4. In a sewing machine, the combination with a work support, a vertically reciprocating needle, a threaded under looper co-operating with the needle below the work support, and an overedge looper co-operating with said under looper and needle to position a loop of thread around and above said work support into position to be entered by the needle during its descent, means for operating said overedge looper including an upwardly extending looper supporting rod, a pivotal supporting connection therefor in which said rod slides, and means for reciprocating said rod longitudinally through said connection and for oscillating said rod during said reciprocations.

5. In a sewing machine, the combination with a work support, a vertically reciprocating needle, a threaded under looper co-operating with the needle below the work support, and an overedge looper co-operating with said under looper and needle to position a loop of thread around and above said work support into position to be entered by the needle during its descent, means for operating said overedge looper including an upwardly extending looper supporting rod, a pivotal supporting connection therefor in which said rod slides, and means for reciprocating said rod longitudinally through said connection and for oscillating said rod during said reciprocations, said reciprocating means including a rock arm pivotally connected to said rod and movable from a point below to a point above a horizontal line passing through the fulcrum of said arm.

6. In a sewing machine, the combination with a work support, a vertically reciprocating needle, a threaded under looper co-operating with the needle below the work support, and an overedge looper co-operating with said under looper and needle to po-

sition a loop of thread around and above said work support into position to be entered by the needle during its descent, and means for operating said overedge looper including an upwardly extending looper supporting rod, a pivotal supporting connection therefor in which said rod slides, and means for reciprocating said rod longitudinally through said connection and for oscillating said rod during said reciprocations, said sliding pivotal supporting connection comprising a supporting bracket, a stud journaled therein, and provided at one end with a vertically extending sleeve for receiving said looper supporting rod.

7. In a sewing machine, the combination with a work support, a vertically reciprocating needle, a threaded under looper co-operating with the needle below the work support, and an overedge looper co-operating with said under looper and needle to position a loop of thread around and above said work support into position to be entered by the needle during its descent, means for operating said overedge looper including an upwardly extending looper rod, a pivotal supporting connection therefor in which said rod slides, and means for reciprocating said rod longitudinally through said connection and for oscillating said rod during said reciprocations, said overedge looper operating mechanism being entirely located on the right-hand side of the needle.

8. In a sewing machine, the combination with a work support, a vertically reciprocating needle, a threaded under looper co-operating with the needle below the work support, and an overedge looper co-operating with said under looper and needle to position a loop of thread around and above said work support into position to be entered by the needle during its descent, means for operating said overedge looper including an upwardly extending looper supporting rod, a laterally adjustable bracket, a stud journaled therein and provided with an opening in which the looper supporting rod is free to slide, and means for reciprocating said rod longitudinally in said support and for oscillating said rod and the supporting stud therefor during the reciprocations of said rod.

In testimony whereof, I affix my signature.

SAMUEL GEORGE TATE.
